YARN CARRIER WITH A REPLACEABLE
YARN GUIDE EYELET

Herman Staub, Wyomissing, Pa., assignor to Textile Machine Works, Wyomissing, Pa., a corporation of Pennsylvania

Application June 28, 1943, Serial No. 492,634

21 Claims. (Cl. 66—126)

1

The present invention relates in general to yarn guide means of either reciprocating or non-reciprocating type, and more particularly to improvements in reciprocating yarn carriers such as those employed in full-fashioned or other flat knitting machines, as well as to yarn guide members or eyelets associated with and forming a part of such yarn carriers.

It is a known fact, although essentially a surprising one, that ordinary textile yarns such as silk, cotton and rayon have a marked grooving or scoring action on the eyelets and like guide members through and over which they run and this in spite of the fact that such eyelets and other guide members for the yarn are made of polished hard materials. Due to such scoring or grooving in the guide element the yarn is damaged by the guide member and often broken, leading to expensive shut downs of production machinery to permit rethreading and also for replacement of the yarn guide members.

The delay due to the need of changing yarn guide members is especially serious in the case of full-fashioned or like knitting machines in which a number of yarn carrier rods of rectangular cross-section are mounted to reciprocate side by side with only a small clearance between adjacent rods. In such a case, the bolts or other attachment means for holding the main plates of the yarn carriers on the yarn carrier rods, except those for the top rod of a group, lie between two rods in such position that their removal is blocked and customarily it is necessary to take out the rod carrying an entire set of yarn carriers in order to change a yarn guide which has become too much worn for further use. When the worn guide is a part of the yarn carrier, then, before or after another carrier has been substituted for the original one, the remaining parts of the carrier need to be reassembled on the holder and the holder and parts must be adjusted to ensure that the yarn guide at the lower end of the carrier is in the correct position.

It is an object of this invention to provide a yarn carrier having a yarn guide construction adapted to minimize the grooving action of the yarn in the guide member.

Another object of this invention is to provide a yarn carrier element, for a knitting machine, with a readily removable guide eyelet.

Another object is to provide a yarn carrier having an eyelet arrangement permitting the eyelet to rotate in use in response to the action of the machine and the yarn.

A further object is to provide a yarn carrier

arrangement for full-fashioned or other flat knitting machines in which all the yarn guide members may be renewed without disturbing the adjustment of any of the remaining parts.

5 A still additional object is to provide a yarn carrier arrangement for full-fashioned or other flat knitting machines in which all the yarn guide elements are renewable while the carrier is in position for use and so formed that the movement of yarn carriers relative one to another is not hindered.

10 A further object is to provide a yarn carrier having a mounting means for an eyelet permitting the eyelet to be readily put in position for use in the carrier and readily removed therefrom.

15 Still another object is to provide a yarn guide member, such as an eyelet, and supporting means therefor adapted to releasably hold the guide member in a sufficient number of different angular positions in use to permit the wear on the guide member to be distributed over substantially three hundred and sixty degrees of arc.

20 With these and other objects in view, which will become apparent from the following detailed description of an illustrative embodiment of the present invention shown in the accompanying drawings, the invention resides in the yarn carrier means, comprising the new elements, method of manufacture, the novel features of construction and arrangement of parts in cooperative relationship, as herein disclosed and hereinafter more particularly pointed out in the claims.

25 35 In the drawings:

Figure 1 is a view of a yarn carrier within the present invention as viewed in the direction of the arrow A in Fig. 2 and showing in connection therewith portions of the yarn carrier

40 rods, a needle bar and a sinker-head of a "Reading" full-fashioned knitting machine;

Fig. 2 is a sectional view taken on the line 2—2 of Fig. 1;

45 Fig. 3 is a view on an enlarged scale of the upper portion of the yarn carrier shown in Fig. 1 and a portion of carrier rod 8 to which it is shown as attached;

Fig. 4 is a section taken on the line 4—4 of Fig. 3;

50 Fig. 5 is a detail view, partly in section, taken on the line 5—5 of Fig. 3; and

Fig. 6 is a detail view showing the upper portion of the yarn carrier shown in Figs. 1 and 3 drawn to a still larger scale than Fig. 3 and taken

before the extreme upper end of said portion has been bent as shown in the remaining figures.

In the drawings and description, only the means and method necessary to a complete understanding of the invention have been specifically set forth; further information as to the construction and operation of other related, usual and well known knitting machine elements, mechanisms, etc., may be found in one or more of the following publications:

3. Booklet entitled—The “Reading” High-Production Full-Fashioned Knitting Machine—which forms a supplement to the above noted 1940 parts catalog of the Textile Machine Works, and which booklet is a publication of the Textile Machine Works, and was copyrighted by the latter in 1940.
4. Pamphlet entitled—Knitting Machine Lectures—published by the Wyomissing Polytechnic Institute, Wyomissing, Pennsylvania, in 1935.

A yarn carrier apparatus within this invention involves means for releasably holding a yarn guide member at the point the yarn enters the carrier apparatus whereby a guide member may be readily exchanged for another in any yarn carrier of a group.

A yarn carrier apparatus within this invention includes holding means for the yarn guide members so compactly arranged that any yarn carrier rod of a group such as are found in full-fashioned knitting machines may be used with any other rod of the group without interference while the yarn guide members are, at the same time, readily renewable by replacement and, preferably, rotatable.

Also yarn carrier apparatus within this invention includes a yarn guide member so formed and mounted as to distribute the wear on the guide member over as much of the surface thereof as possible and thereby to minimize the grooving action of the yarn.

In machines utilizing reciprocating yarn carriers, it is preferred that the yarn guide member be a ring type eyelet and the mounting means therefor adapted to permit the eyelet to rotate and thereby distribute the wear around the entire inner circumference of the ring. Preferably, the eyelet according to this invention is made of steel or a metal alloy and is symmetrical both with respect to a central axis generally parallel to the course of the thread through the eyelet and with respect to a plane at right angles to said central axis. It is thereby possible to readily and economically machine the eyelet to the desired shape and then to heat treat the eyelet to harden it to a high degree without distortion. The resulting eyelet type of yarn guide member is readily manufactured in quantity at low cost and is sufficiently hard so that, especially when mounted for use in a yarn carrier or like supporting means permitting it to rotate or to be shifted by hand to different angular positions, it gives long service. The yarn carrier can be readily and economically manufactured to per-

mit the yarn guide eyelet member not only to rotate but to permit it to be easily inserted into and removed from the supporting means, thereby facilitating the substitution of a new yarn guide member for a worn one or the changing of the angular position of a non-rotating yarn guide member. The preferred construction in a yarn carrier is one which permits the yarn guide member to be inserted therein and removed therefrom by a simple snap action.

Referring to the drawings in detail, a group of closely spaced parallel yarn carrier rods designated 1 to 8, inclusive, from bottom to top, are shown in Figs. 1 and 2. Said group of rods are parts of the standard “Reading” type footer, legger or single unit knitting machine and are mounted to reciprocate in slots in brackets, one of which is shown at 9 in Fig. 2, bars such as 9A being provided, one bar for each bracket to hold the rods in the slots in the brackets. Rods 1 to 8 serve as parts of the means for delivering yarn to the knitting elements of such a machine, said elements including a row of needles 10 mounted on a needle bar 11 and cooperating sinkers 12 and dividers 13 for measuring yarn laid to the needles and for dividing it, the sinkers and dividers arranged alternately. The sinkers and dividers are shown as mounted to reciprocate in a sinker-head structure including a base 14 and a cap 15, said structure mounted on a centre bed, a portion of which appears at 16. Mounted on the cap 15 is a verge plate 17 for limiting the motion of the sinkers and dividers in the direction toward the needles 10. As the machine is operated, a fabric 18 is formed on needles 10 by the cooperative action of the needles, sinkers, dividers and other cooperating knitting elements not shown, from yarn laid to the needles coincident with the reciprocation of one or more yarn carrier rods. The means for operating the elements previously mentioned are not shown herein and need not be further mentioned since, as above indicated, they are well known.

Shown as fixed to yarn carrier rod 8 by bolts 19 or other suitable means (Figs. 1, 2 and 3) is a yarn carrier according to the present invention designated generally as 20, each rod in group 1 to 8 being understood to have a set of yarn carriers thereon, one for each knitting section. Carrier 20 may be of somewhat the same general type as that shown in the patent to Gastrich, No. 2,092,619, of September 7, 1937, and is shown as comprising a supporting plate or holder 21 directly bolted to rod 8 and a finger portion 22 adjustably connected to the under side of plate 21 by bolts 23 or other suitable means. Also adjustably connected to plate 21 by bolts 23 is a washer plate 24, lying above plate 21 and optionally of relatively small size and of triangular form as shown.

The group of yarn carrier rods 1 to 8, inclusive, are set close together as appears in Fig. 2 but, as will hereinafter more fully appear, the novel yarn guide members or eyelets and the means for holding them on the carriers are so formed and arranged that not only are the guide members renewable or replaceable when the carriers are in position for use but each carrier can pass the carrier or carriers next adjacent thereto without hindrance when in use, so that the operator's choice of a rod is not limited by possible interference. The yarn carrier rods 1 to 8, or equivalent elements, are reciprocated in use, although often only one at a time and usually not more than three at once. In the well-known full-

fashioned knitting machine, they are reciprocated between end stops when in use and are driven by friction boxes on a reciprocating friction-box rod through arms which may each be connected with and disconnected from a given rod of a group as desired. The yarn carrier rods shown generally reciprocate between end stops which limit the lengths of their paths when laying yarn, but the stops may be moved out of the paths of the rods to permit the rods to pass them and to thereby be laid out by hand, some on one side of the knitting field and some on the other, when not in use. When so laid out, the yarn carriers on the carrier rods laid out on a given side of the knitting field lie one above another and so may prevent ready access to the yarn guide members of those yarn carriers in the lower carriers of those laid out on one or the other side of the knitting field. However, when the machine is stationary, any given rod having a yarn carrier thereon including a yarn guide member needing to be changed may easily be moved out so that the yarn carriers thereon lie in the knitting fields, in which location all yarn guide members in carriers on the rod are readily accessible.

It will be seen that carrier 20 extends downwardly and forwardly from the rod 8 to a point near the needles and sinkers. In the arrangement shown, four yarn guide members are included in the yarn carrier 20. One of said members, 25, is at the upper end of plate 21 and therefore is at a higher level than the rod; a second, 26, at the upper end of plate 24; a third, 27, at the lower end of plate 24; and a fourth, 28, at the lower end of finger 22. Guide members 25, 26 and 27 are shown as eyelets of the improved construction, while member 28 is a replaceable yarn tube of known form not related to the present invention. In use, yarn 29 from a yarn source not shown is threaded down through members 25, 26, 27 and 28 and its lower end held fast until after the yarn has been formed into one or more courses of knitted loops, when it can be released. Guide members 25, 26 and 27 are shown as substantially identical and are all mounted so as to rotate in use.

Each guide member 25, 26 and 27 is generally annular in form, being of ring or eyelet shape having a generally cylindrical aperture 30 therethrough, as shown in Figs. 4 and 5, and symmetrical with respect to the longitudinal axis of aperture 30. Aperture 30 is, however, flared outwardly somewhat at its ends as shown at 31 to provide a smooth bevelled inlet and thus avoid too sharp an edge which would scrape or abrade the yarn 29, especially as the yarn enters the eyelet 25 and leaves the eyelet 27, at which points a noticeable angle is formed in the yarn. Each eyelet, however, is symmetrical with respect to its central plane transverse to the central axis of its aperture, so that it is immaterial which end of any eyelet is used as inlet and which as outlet for the yarn. Also, each eyelet 25, 26 and 27 has a circumferential groove 32 in its said central transverse plane in which the supporting means for an eyelet is seated when the eyelet is in use.

The mounting, holding or supporting means for the guide member 25 is such that not only can the member rotate in use, but it can be readily pressed into position in the holding means and removed therefrom whenever it is desired to change one eyelet or guide member for another.

Said supporting means comprises a pair of spaced arms 33-33 which are of light enough cross section and long enough to have a certain

amount of spring. Arms 33 for the mounting means for eyelet 25 are shown as projecting from the plate 21 and for the most part bent only slightly out of the plane of the plate. Near their outer ends, arms 33 are shown as bent at an angle to form terminal fingers 34-34 so that pressure tending to spread fingers 34 not only acts to spring arms 33 apart but also tends to twist arms 33 to further increase the distance between the fingers 34. Fingers 34 of arms 33 are shown as bent at substantially right angles to the plate 21, however, the invention is not limited to a particular angle. Therefore, a yarn guide member such as eyelet 25 can be quickly and conveniently assembled in its supporting means by taking the eyelet between the thumb and forefinger or by gripping it with pliers and pressing it between fingers 34, which yield to receive it. To facilitate thus inserting the eyelet, the tips of fingers 34 are rounded at 35-35 as best shown in Figs. 5 and 6. The distance between the inner faces of rounded portions 35 is normally somewhat less than the minimum outer diameter of the eyelet 25 at the groove 32. Just inside the rounded portions 35, fingers 34 are cut out to form recesses bounded by circular arcuate surfaces 37 which conform to the outside diameter of the eyelet at the groove 32. Preferably, the diametric distance between the arcuate inner surfaces of the fingers is, however, slightly greater than the normal minimum outer diameter of the eyelet at the groove 32 so that there is a clearance between them as shown in Fig. 5 and the eyelet is free to revolve in the fingers 34 which normally support it.

The supporting means shown for eyelets 26 and 27 are of the same type as that for eyelet 25 and are shown one at each end of the washer plate 24. The supporting means for the eyelets 26 and 27 comprise arms 38-38 and 39-39, respectively, and fingers 40-40 and 41-41, respectively, the fingers in each case being set substantially at right angles to the arms. Also, arms 38 and 39 are integral with the plate 24 and fingers 40 and 41 are integral with the arms. Further, although the means for supporting eyelets 26 and 27 are of slightly different proportions from that for supporting eyelet 25, they will not be further described, except to say that the eyelets 26 and 27 are readily releasable from and insertable in their supports and are preferably rotatable therein.

It will be understandable from the foregoing that any yarn guide member or eyelet 25, at the upper end or intermediate portion of a holder 21 of a yarn carrier arrangement within this invention, can be removed and replaced by another without disturbing the holder and therefore without requiring that the yarn carrier rod to which the holder is fixed be removed from the brackets. Similarly any eyelet 26 or 27 can be removed and replaced without disturbing the adjustment of the plate 24 from which it is supported. Further, the holder means on each holder 21 and on each washer plate 24 for holding guide members or eyelets 25, 26 and 27 require so little room in the direction at right angles to the planes of the plate 21 and the plate 24 that the holding means do not hinder a carrier from passing above or beneath another carrier immediately adjacent to it in the group.

When it is desired to change a yarn carrier member such as one of the eyelets 25, 26 and 27 or the delivery tube 28, the yarn carrier will, in general, be one in use, so that it will either come

to rest at the end of a yarn laying stroke in a position in which all the yarn guide members are readily accessible to the machine operator or else it can be readily moved into such a position that all of such guide members will be so accessible by turning over the machine a portion of a revolution either by the motor or by hand. Such carrier rods as are not in use and therefore are "laid out" at one side or the other of the knitting field, insofar as may be necessary, may be moved by hand when the machine has been stopped so that any yarn carrier on which it is desired to change a yarn guide member or eyelet may be readily accessible for this purpose.

In operation, yarn 29 is threaded through eyelets 25, 26 and 27 and tube 28, the yarn carrier rod 8 and/or such other rods or rods as may be in use is or are reciprocated rapidly by the known "couliering" means or its equivalent so that yarn is drawn from a source (not shown) and laid along the needle row as will be clear from Figs. 1 and 2. Owing to the inertia of the yarn, it swings back and forth during operation of the machine, thereby turning with it the eyelets 25, 26 and 27. Also, the jars given the carrier rods 1 to 8 during operation, and especially during stopping and reversing them, cause the rotatably mounted eyelets 25, 26 and 27 to jump, slip or skip with respect to the yarn and thereby turn the point of contact between the yarn and eyelet through a complete revolution at frequent intervals in use. Such rotation of the eyelet in use in response to the action of the yarn and/or the machine distributes the wear over the entire inner surface of the eyelet, thereby greatly lengthening its useful life and diminishing yarn damage. However, in case it is preferred not to permit the eyelets or other yarn guides to rotate in use, this is readily provided for within this invention by reducing the spacing between the opposed arcuate surfaces of the fingers 35 to eliminate the clearance between them and the eyelet such as 25. Nevertheless, owing to the ease with which the eyelets can be snapped into and out of their supports, they can be taken out and turned by hand from time to time to distribute the wear of the yarn on the eyelets. As shown, the arms 33, 38 and 39 are integral with the plate 21, but the invention is not limited to this.

In the manufacture of an eyelet supporting means on a plate such as 21 or 24, the plate preferably is substantially plane at first and in this condition portions are struck out to form the arms 33 or 38 and 39 and the socket or sockets for the eyelet or other yarn guide member or members bounded by arcuate surfaces 37. The arms 33, 38 and 39 are thereby formed integral with plate 21 or plate 24, but they may be welded, brazed or otherwise affixed to the plates. The arms 33, 38 and 39 are bent to form fingers 34, 40 and 41, respectively, thereon having the sockets for the guide members therein and at the same time to form angles in the arms but preferably near the outer ends of the arms. As shown, the fingers are set at angles to the arms, but this also is optional. The bending of the arms to set the fingers at angles thereto is done after the arms have been formed in the plates when the arms are integral with the plates. Otherwise the bending may be done at any time. The main portion of plate 21 may be bent as shown in Fig. 4 at the time of bending the fingers but preferably this is done at the time of striking out material between the arms 33.

The improvements specifically shown and described by which I obtain the above results, can be changed and modified in various ways without departing from the invention herein disclosed and hereinafter claimed.

I claim as my invention:

1. In a flat knitting machine, a group of reciprocating members having yarn carriers fixed thereto, each of said carriers including means including arms spaced and offset at their free ends and fixed to the carrier at their other ends for replaceably holding a yarn guide member at a point removed from its yarn delivery end and a yarn guide member releasably held in said means.

2. In a flat knitting machine, a group of reciprocating members having yarn carriers fixed thereto, each of said carriers including means including arms spaced and offset at their free ends and fixed to the carrier at their other ends for replaceably holding yarn guide members at points along its length, and yarn guide members releasably held in said means, each of said carriers passing any other in use.

3. In a flat knitting machine, a group of reciprocating members having yarn carriers fixed thereto, each of said carriers having means for rotatably and replaceably holding a yarn guide member at a point removed from its delivery end, said means extending in part at an angle to the part of the yarn carrier on which the means is carried, each of said carriers passing any other in use.

4. A yarn carrier comprising a member provided with supporting means including bifurcated arms projecting somewhat transversely of the general plane of the carrier and adapted to releasably hold an eyelet in position to guide yarn in the direction of the length of the carrier, and an eyelet rotatably mounted in said supporting means and having a groove into which said arms project.

5. In a yarn carrier having a reciprocating action and subject to jars in use, an eyelet receiving yarn and directing the yarn lengthwise of the carrier and rotatably mounted thereon by means extending somewhat transversely of the general plane of the carrier, said jarring of the carrier assisting rotation of said eyelet.

6. In a flat knitting machine, in combination, a reciprocating yarn carrier, an eyelet on the carrier thru which the yarn passes, and transversely extending bifurcate supporting means on the carrier in which the eyelet is releasably and rotatably mounted.

7. In a flat knitting machine, in combination, a reciprocating yarn carrier comprising a member provided with transverse bifurcate supports adapted to releasably hold eyelets in position to guide yarn in the direction of the length of the carrier, and eyelets rotatably mounted in said supports.

8. In a flat knitting machine, in combination, a yarn carrier reciprocating with respect to its yarn supply and subject to jars from the machine in use, an eyelet, and a transverse bifurcate eyelet supporting means on the carrier and having snap action with respect to said eyelet so that the eyelet may be readily forced into operative position in the supporting means and releasably held in said operative position, the eyelet rotating in its supporting means in use in response to jars from the machine and the action of the yarn.

9. A supporting means for a yarn guide mem-

ber including a plate having a pair of spaced arms fixed thereon and bent to form an angle relatively near their outer ends and having opposed arcuate recesses, the faces of which are adapted to hold an eyelet in use, and to permit the ready release and replacement of the eyelet by a combined spreading and twisting action of the arms.

10. A yarn carrier comprising a plate to be directly fixed to one of a group of reciprocating carrier rods and having a finger fastened to one end and a means including arms spaced and offset at their free ends and fixed to the carrier at their other ends for releasably holding a yarn guide member fastened to its other end and adapted to project clear of the group of rods, whereby a guide member in said means may be readily exchanged for another without needing to disturb any of the group of rods.

11. A yarn carrier having a holder member to be directly fixed to one of a group of yarn carrier rods, a yarn guide member at each end of said holder member and yarn guide means intermediate said guide members and including arms spaced and offset at their free ends and fixed to the carrier at their other ends, said guide members and guide means all replaceable without disturbing said holder member.

12. A yarn carrier comprising a holder member to be directly fixed to one of a group of yarn carrier rods, a carrier finger fixed to one end of said holder member, a means at the other end of said holder member for releasably holding a yarn guide member, a washer plate held at a point of connection between said holder member and said finger, and means for releasably holding yarn guide members, one at each end of said washer plate, and including bifurcated arms upstanding from the plane of the washer plate.

13. A yarn carrier having a holder member to be directly fixed to one of a group of yarn carrier rods, a yarn guide member at each end of said holder member and yarn guide means intermediate said guide members and including a plate supported on said holder member and including arms spaced and offset at their free ends and fixed to the plate at their other ends, said guide members and guide means all replaceable without disturbing said holder member.

14. A yarn carrier comprising a holder member to be directly fixed to one of a group of yarn carrier rods, a carrier finger fixed to one end of said holder member, a replaceable yarn guide member at the other end of said holder member, a washer plate held at a point of connection between said holder member and said finger, yarn guide members, one at each end of said washer plate, and bifurcated arms upstanding at least one from said holder member and at least one from said washer plate and integral therewith for releasably holding said yarn guide members.

15. In a flat knitting machine, a group of reciprocating members having yarn carriers fixed thereon, each carrier adapted to pass any other carrier in use, each having a plurality of yarn guide members in addition to a yarn delivery

5 tube, all said plurality of guide members renewable when the reciprocating members are all in position for use, and readily releasable means for holding each of said guide members including bifurcate arms.

16. In a flat knitting machine, a group of reciprocating members having yarn carriers fixed thereto, each of said carriers including a holder, a finger fixed to said holder and a washer plate 10 at the juncture of said holder and finger, said holder having means for replaceably holding a yarn guide member at the end removed from said finger and said washer plate having means at both ends for replaceably holding yarn guide members, each of said carriers passing any other 15 in use.

17. In a full-fashioned knitting machine, the combination with a reciprocating yarn carrier rod of a yarn carrier fixed thereto and comprising portions extending in opposite directions from said rod, and means including bifurcate arms in said portions for releasably holding yarn guide members.

18. In a flat knitting machine, a group of reciprocating members having yarn carriers fixed thereto, each of said carriers having means including arms having spaced free ends with the means fixed to the carrier at its other end and adapted for rotatably and replaceably holding a yarn guide member at a point removed from the delivery end of the carrier, said means extending in part at an angle to the part of the yarn carrier on which the means is carried, each of said carriers passing any other in use.

19. In a flat knitting machine, a group of reciprocating members having yarn carriers fixed thereto, each of said carriers including a holder, a finger fixed to said holder and a washer plate at the junction of said holder and finger, said holder having means for replaceably holding a yarn guide member at the end removed from said finger and said washer plate having means at both ends each including bifurcate arms for replaceably holding yarn guide members, each of said carriers passing any other in use.

20. A yarn carrier structure for full-fashioned knitting machines having means intermediate its ends for holding yarn guide eyelets comprising a plate portion having arms with spaced free ends lying approximately at right angles to the plate and adapted to permit eyelet members to be readily inserted therebetween and removed therefrom.

21. A yarn carrier including a base having a generally plane rear portion and a generally plane front portion tilted relative to said rear portion, a yarn guide finger extending from said front portion and generally parallel thereto, a replaceable yarn guide tube removably mounted on said rear portion and extending generally parallel thereto, and a second replaceable yarn guide tube removably mounted generally parallel to said front portion.

HERMAN STAUB.
